BAND SAW

Frederick S. Brennan, Evanston, Ill., assignor to Rockwell Manufacturing Company, Pittsburgh, Pa., a corporation of Pennsylvania

Application April 15, 1957, Serial No. 45,730

Term of patent 14 years

(Cl. D93—3)

I claim:

The ornamental design for a band saw, as shown.
